INVENTOR.

BY

Richard J. Krogman
ATTORNEY.

UNITED STATES PATENT OFFICE.

JOE KROGMAN, OF NEW HAMPTON, IOWA.

WHIFFLETREE-CONNECTOR.

1,324,556.

Specification of Letters Patent. Patented Dec. 9, 1919.

Application filed March 18, 1919. Serial No. 283,298.

To all whom it may concern:

Be it known that I, JOE KROGMAN, a citizen of the United States, residing at New Hampton, in the county of Chickasaw and 5 State of Iowa, have invented certain new and useful Improvements in Whiffletree-Connectors, of which the following is a specification.

The invention provides novel means for 10 connecting a whiffle-tree to a pole or tongue whereby to prevent the swingle-trees from trailing upon the ground or coming in contact with the heels or back legs of the team hitched to a wagon or the like to be drawn 15 over the road or other surface.

In accordance with the invention provision is had for disposing the whiffle-tree at different relative elevations according to the character of the load, the construction 20 being such as to admit of the change being easily and quickly effected.

The drawing illustrates a preferred embodiment of the invention. However, it is to be understood that in adapting the same 25 to meet different conditions, various changes in the form, proportion, and minor details of construction may be resorted to without departing from the nature of the invention as claimed hereinafter.

30 Referring to the drawing hereto attached, Figure 1 is a detail view in elevation showing the invention applied to a pole or tongue which is hitched to the runners of a sled.

35 Fig. 2 is a top plan view of the parts shown in Fig. 1.

Fig. 3 is a transverse section on the line 3—3 of Fig. 1 looking to the left as indicated by the arrows.

40 Fig. 4 is a detail longitudinal section showing the parts on a larger scale.

Corresponding and like parts are referred to in the following description and indicated in the several views of the drawing by 45 like reference characters.

The invention is adapted for application to a pole or tongue 1 which may be hitched to any type of vehicle to be drawn by means of a team. As illustrated the pole or tongue 50 1 is connected at its rear end to a cross piece 2 which in turn is coupled to the runners 3 of a sled. A hammer strap 4 is connected at its rear end to the pole or tongue 1 and inclines upwardly and forwardly, thence 55 parallel with the pole or tongue to a short distance, as indicated at 5. An auxiliary

strap 6 is secured at its rear end to the inclined portion of the hammer strap 4 and inclines upwardly and forwardly and terminates in a portion 7 which parallels the 60 portion 5 of the hammer strap 4. A strap 8 is placed upon the pole or tongue 1 and an end portion curves rearwardly, thence forwardly, as indicated at 9, the upper end of the curved portion underlapping and making contact with the rear portion of the part 5 of the hammer strap. A clip 10 connects the curved portion 9 of the strap 8 with the pole or tongue, the upper portion of the clip 10 extending forwardly and engaging openings near the edges of the part 7, as indicated most clearly in Fig. 3. A bolt or like part 11 passes through the forward portions of the several straps 7, 5 and 8 and through the pole or tongue 1 and is 70 adapted to receive spacing elements 12. The bolt or like part 11 also receives the whiffle-tree 13.

The spacing elements 12 consist of blocks 80 of circular form which are centrally apertured to receive the bolt or fastening 11. Each of the blocks 12 is of a length corresponding to the thickness of the whiffle-tree so that said whiffle-tree may be adjusted upon the bolt 11 to occupy any one of three 85 positions. As indicated in Fig. 1 the whiffle-tree is disposed above the forward portion 5 of the hammer strap and below the forward portion 7 of the auxiliary strap. The whiffle-tree may be adjusted so as to 90 occupy the position of either one of the spacer elements 12 so that one of such elements may be either below or above the whiffle-tree. The construction is such as to admit of the whiffle-tree being adjusted to 95 different relative positions according to the nature of the load. For a light load it is preferred to have the whiffle-tree occupy the highest position above the pole or tongue. For a heavier load it is desirable 100 to have the whiffle-tree occupy an intermediate position which is nearer the pole or tongue. For a heavy load the whiffle-tree should be supported directly upon the pole or tongue. By adjusting the whiffle-tree to 105 different relative elevations it has been found that the swingle-trees do not tend to trail upon the ground or strike the heels or back legs of the team.

The foregoing description and the drawing have reference to what may be considered the preferred, or approved form of

my invention. It is to be understood that I may make such changes in construction and arrangement and combination of parts, materials, dimensions, et cetera, as may 5 prove expedient and fall within the scope of the appended claims.

Having thus fully described my invention, what I claim as new and desire to secure by Letters Patent is:—

- 10 1. In combination, a pole or tongue, a hammer strap, an auxiliary strap having its forward portion spaced from the forward portion of the hammer strap, a fastening supported in the pole and the forward portions of the straps, a whiffle-tree adjustable on the fastening and spacing elements mounted upon the fastening and inter-
- 15

changeable with the whiffle-tree to admit of the latter occupying different elevation relatively to the pole.

- 20 2. In combination, a pole, a hammer strap, a second strap having its rear portion curved upwardly and forwardly, a fastening connecting the two straps to the pole and a clip engaging the rear curved portion of the second strap and connecting it to the pole.
- 25

In testimony whereof I affix my signature in presence of two witnesses.

JOE KROGMAN.
